UNITED STATES PATENT OFFICE.

ROBERT C. MATHERS, OF WYOMING, NEW JERSEY, ASSIGNOR TO WESTERN ELECTRIC COMPANY, INCORPORATED, OF NEW YORK, N. Y., A CORPORATION OF NEW YORK.

RECEIVING SYSTEM FOR TELEGRAPHIC SIGNALS.

Application filed June 19, 1918, Serial No. 240,792. Renewed March 27, 1925.

This invention relates to wave shaping or correcting means for systems having transmission characteristics which distort the form of waves transmitted thereover, and has for an object to correct at least partially for such distortion, or to compensate in part at least for the unequal attenuation, so as to produce in the waves as eventually received and translated, a more faithful 10 production of the original waves.

It is well known that telegraphic or other signals transmitted over long conductors of high capacity such as submarine cables are subject to serious distortion, which distortion increases with the speed of signaling.

The purpose of this invention is to correct this distortion so that transmission may be carried on at a higher speed, or so that the wave form and power of the received signals 20 may be made suitable for operating devices which would not otherwise respond properly.

One feature of the invention consists in inserting between the cable terminal and 25 the responsive device to be actuated a connecting line in the form of a network, or series of networks, made up of resistance, inductance and capacity, the values of which are so chosen and the arrangement of which 30 relative to one another is such that there are added to the received signal wave derivatives thereof in such proportion that the summation current produced has a wave form closely approximating the original 35 transmitted wave.

In other words, where the transmitted wave is of the customary square-top form, it becomes possible by employing this invention to differentiate the received 40 pulses as gradually as the cable integrated the impulses originally transmitted, and thus to reproduce for the actuation of the receiving mechanism an arrival wave having the desired sharp-head, flat-top and 45 long, gradual tail.

Such a process of differentiation necessarily involves considerable diminution in the power value of the signals, and in certain cases it therefore becomes necessary to 50 provide, and by this invention there is provided, an amplifier or system of amplifiers for increasing the power of the signals to the degree required for effective reception at the cable terminal, or for retransmission 55 over a land line or another cable.

Such amplification should be accomplished without the introduction of any additional distortion, and it is therefore preferable to employ for this purpose vacuum tube amplifiers of the thermionic type. 60

The distortion correction or differentiation may take place and be completed prior to amplification, or, as in the preferred embodiment of the invention, such a differentiation and amplification may take place in 65 alternate, successive steps. The latter arrangement has certain advantages, especially where vacuum tube amplifiers of the thermionic type are employed, for the reason that due to the unilateral conductivity of 70 such amplifiers, any reaction of one correcting network on the preceding network is eliminated, and it is possible to effect the correction with greater exactness.

It will, of course, be evident that in some 75 instances where the cable distortion is not serious, but where the attenuation is large, amplifiers alone may be used without the correcting network, and conversely, where distortion is great but the attenuation is 80 relatively small, the correcting networks may be used without amplifiers.

In employing amplifiers of the vacuum tube type in telegraph systems, particularly 85 where such systems are worked on the duplex principle, special precautions must be taken to protect the amplifiers against unbalanced potentials, due to the operation of the local sending mechanism. This is particularly the case where the amplifier employed is of the vacuum tube type, and is 90 unsymmetrical as to its exposure to ground. In the system of this invention there is provided for this purpose a special form of transformer having a grounded shield between its primary and secondary windings 95 for connecting the amplifier to the cable system.

The invention will be better understood, 100 and other novel features will more readily appear from a consideration of the accompanying drawings. Fig. 1 of the drawings illustrates a circuit arrangement for providing duplex service over a submarine cable, and shows an arrangement for correcting and amplifying the received signals; 105 Fig. 2 shows another embodiment wherein the distortion correction and amplification take place in alternate successive stages; Fig. 3 shows an arrival curve for submarine 110

signals with the first, second, third and fourth derivatives of such curve; Fig. 4 illustrates various forms of derived curves; and Figs. 5 to 13 inclusive show various 5 modifications of the correcting networks.

Referring to Fig. 1, submarine cable 5 terminates in a duplex circuit comprising the two inductive ratio arms 6 and 7, the variable inductances 8 and 9 and the potentiometer resistance 10 to which the customary local transmitter 11 is connected. The usual 10 artificial line 12 is provided for balancing the cable impedance. Connected across the ratio arms in the position of the usual receiving apparatus is the distortion correcting line, made up of a plurality of series elements 13, and shunt elements 14. The actual design of such networks is capable of a variety of modifications, depending upon 15 the extent to which the signals have been distorted by the cable and upon the wave form ultimately desired.

For example, in many cases a very simple network such as that shown in Fig. 5 may be 20 employed, in which the shunt element consists of an inductance L having a predetermined finite resistance, or having an extra resistance r of the proper value in series with it, and in which the series element 25 consists of a capacity C . The capacity C may be shunted by a resistance r_0 as in Fig. 6, or by a combination of resistance r_0 and inductance l_0 , as in Fig. 7. Similarly, the resistance r in the shunt circuit 30 may be shunted by a capacity c_0 as in Fig. 7, or the resistance r and inductance L may together be shunted by the capacity C_0 , as in Fig. 9.

Other resistances r_1 may be added to both 35 the shunt and series elements, as in Figs. 8 and 9, both as a protection against free oscillations and as a means for proportioning the amounts of the different derivatives to be combined in the final wave.

In extending the system further by adding 40 more elements or sections to the correcting network, the respective amount of differentiation introduced by series and shunt elements may be proportioned in any relative 45 value. In fact, the differentiating action of one or the other may, in the latter networks, be eliminated by reducing the network to one of the forms of Figs. 10, 11, 12 and 13. The advantage of the forms shown 50 in Figs. 12 and 13 is that there is no danger of free oscillations, as neither contains both capacity and inductance. The requirement 55 to be met in the design of such a correcting system is that the combined attenuation for 60 steady state frequencies for the cable and correcting system together shall be fairly uniform within the range of signaling frequencies, or expressed in other words, the product of the attenuation in the cable by 65 the attenuation in the correcting system shall

be substantially a constant within the signaling range. When this requirement is met or approached, by using any of the types of networks disclosed by applicant, the correcting network will give a restored wave of 70 a shape approaching that of the transmitted wave, so that not only will the amplitudes of the different frequency components have been restored but the phases of the various components will also have been in a measure 75 restored. That is, the propagation constant of the corrective network is reciprocal in nature to that of the line, and counteracts the distortion of the line as regards both the amplitude and the phase of the waves 80 transmitted through it. Restoring the phase relations of the frequency components to the relations existing in the waves as transmitted involves providing a higher rate of propagation in the correcting network for those 85 components of the waves which were less rapidly propagated by the line or cable, and vice versa.

The action of these various series and shunt elements in effecting the change of 90 wave form may best be considered in connection with Fig. 3. In this figure, assume that A represents the wave form of the arrival current passing from cable through the ratio arms 6, 8, 10, 9, 7 to earth, caused by 95 the application of a steady potential to the sending end of the cable. Such a current will develop between the terminals 16 and 17 a voltage which is roughly the first derivative B of curve A. If the impedance of 100 the path through the ratio arms is small compared to the cable impedance, and if there were no resistance in series with it, this first derivative would be very closely approximated. On applying this voltage 105 to the first series element, the current through that element, if it be a condenser only with impedance high compared to the impedance of the ratio arms, will be the second derivative C of the arrival curve A. Similarly, the voltage across the first shunt element will be the third derivative D, and the current through the second series element 110 will be the fourth derivative E. However, as the shunt inductances have resistance in series, and the series condensers have shunt resistances, the final result is not a derivative curve of any one degree but the sum of the original arrival curve and certain amounts of each of the other derivative 115 curves, which amounts will depend upon the impedances in series with the shunting inductances, and upon the impedances shunting the condensers. There will thus be produced at the terminals of the last section 120 of the correcting network a current wave having approximately the form of curve H, Fig. 4, the characteristic feature of which is the steep front and relatively flat top. When the time t_1 required to reach the max- 125 130

imum point Y_1 is less than the time required for transmitting a dot impulse, it is readily seen that the received signals will be substantially perfect though with rounded corners.

While in simplex operation it is generally possible to apply this resulting corrected wave form directly to the input of the amplifier system, in duplex operation it will 10 in general be preferable to eliminate metallic connection between the amplifier and cable. This is preferably done by means of a special form of transformer 18. Such a transformer necessarily introduces some distortion, but by proper design this distortion 15 can be controlled so that it will not sensibly interfere with the proper recording of signals. For example, in translating the corrected arrival curve H of Fig. 4 to the 20 amplifier system, an ordinary transformer would distort the curve to the form corresponding to curve J , whereas a properly designed transformer such as that provided by this invention will prolong the curve as 25 shown in curve I .

The criterion for such a properly designed transformer is that the ratio of inductance in henries to resistance in ohms in the primary or cable side of the transformer shall be greater than the time in 30 seconds which may be covered by the maximum probable number of consecutive impulses of the same polarity in the telegraphic code employed.

35 The amplifying system is shown in Fig. 1 as a three-stage amplifier employing vacuum tube elements of the well-known thermionic type. The filaments or electron-emitting cathodes 19 of these amplifiers are 40 connected serially in circuit with a source of heating current 20. Resistances 21 are inserted in this heating circuit for the purpose of maintaining the respective input electrodes 22 negative with respect to the 45 filaments 19. The output electrodes or anodes 24 are maintained positive with respect to the filaments 19, by means of a direct current source 25 which is connected to the several anodes 24, in multiple, through 50 the impedances 26.

The operation of such a system is now so well understood as to need only casual reference here. Suffice it to say that changes 55 in potential are developed across the terminals of the secondary winding 18 by current changes in the primary thereof, thus producing differences of potential between the input electrode 22 and filament 19 of the first amplifier, which potential changes set up a 60 corresponding varying current in the output circuit of this amplifier, said output circuit including the anode 24, filament 19, resistance 27 and condenser 28. This in turn sets up a potential variation across the terminals of the resistance 27, which in turn

acts on the input circuit of the second amplifier to produce in its output circuit a varying current, and therefore to set up across the terminals of the resistance 29 a potential variation which in turn controls the current in the output circuit of the third, and in this case, the last amplifier.

The receiving device 30 to be actuated may have resistance-condenser coupling to the last output circuit, as shown in Fig. 1, or a transformer coupling, or the output circuit may be connected to a second transmission line, either a cable or a land line, the receiving device to be actuated being located at the other end of such cable or land line. 80

Inasmuch as such amplifying systems are customarily grounded, as at 31, the operation of the transmitting apparatus 11 would, if steps were not taken to prevent it, cause 85 a fluctuation in the potential of the terminal 32 of transformer 18 with respect to ground. Such a fluctuation would, of course, be amplified in the amplifying system, and might cause serious difficulty in the reception of 90 signals simultaneous with such local transmission. By inserting between the primary and secondary windings of the transformer 18 a grounded shield 33, the secondary winding is effectively shielded from such fluctuating potentials, and this difficulty is done away with. In practice it is furthermore found desirable, owing to the extreme sensitivity of the amplifier apparatus, to shield 95 the complete amplifier system from extraneous disturbances, such as stray fields, by enclosing the apparatus in an iron box, preferably lined with copper. Such a shield is indicated by the dotted line in Fig. 1. 100

In the arrangement of Fig. 2 the distortion 105 correction or differentiation of the received signals and their amplification are each effected in alternate succeeding stages. Here the shielded transformer 18 is preferably connected so that its primary winding comprises the two fixed ratio arms 6 and 7, the secondary winding being directly connected to the input circuit of the first amplifier. Under certain conditions it will be preferable 110 to connect shunt elements 14 across the terminals of each of the windings 6, 7. Between the first and second amplifiers are inserted the two shunt networks 14 and the series network 13. One of the shunt networks 14 may also serve the purpose of the 115 impedances 26 of Fig. 1, and is so illustrated. A second set of correcting networks is inserted between the second and third amplifiers, while other correcting networks may be inserted between other amplifying stages, 120 if desired. The main advantage of the arrangement of Fig. 2 is that the amplifiers are unilaterally conductive and thus act as an effective barrier to any reaction by the 125 second correcting stage on the first and by 130

- the third on the second. This makes it possible to design each correcting stage independently without reference to the stage which is to precede it in the system. It 5 will be obvious that the system is by no means limited to three-stage amplification, that any number of amplifying stages may be employed, and that the amplifying and distortion correction stage may be combined 10 in any arrangement, the primary requirement being that there is produced at the terminals of the receiving device 30 a wave of such shape as most effectively to operate such receiving device, and of sufficient amplitude to cause its positive response.

It will further be obvious that the correcting networks which have been disclosed are not limited in their operation to any particular frequency values, but that, depending on their constants, they may be applied to other frequency ranges than those employed in submarine cable telegraphy, so that the invention in its broader aspects relates to wave transmission systems generally.

What is claimed is:—

1. The combination with a telegraph conductor, of a responsive device, a connecting line between said conductor and said device, the electrical constants of said line being so chosen that the product of the attenuation in said conductor by the attenuation in said line shall remain substantially constant within the range of signaling frequencies transmitted over said conductor and said line.

2. The combination with a submarine cable, of an electric discharge repeater having a cathode, an anode and an impedance control element for amplifying signals received from said cable, and a transformer having a primary winding connected to said cable and its secondary winding connected to the input circuit of said repeater, the ratio of inductance to resistance in said primary winding being greater than the time in seconds covered by the maximum probable number of consecutive impulses of the same polarity occurring in the telegraphic code employed.

3. In combination with a telegraph conductor, an electric discharge repeater for amplifying signals received from said conductor, said repeater having a cathode, an anode and an impedance control element, a transformer having its primary winding connected to said conductor and its secondary winding connected to said repeater, and a signal correcting network bridged across the terminals of said primary winding.

4. The combination with a telegraph conductor, of a duplex network, a transformer having a plurality of windings, two of said windings being included in the two ratio arms of said duplex network respectively,

an amplifying and distorting system having its input circuit connected to another winding of said transformer, and a responsive device connected to the output circuit of said system.

5. The combination with a signaling conductor of a responsive device for indicating the arrival of signaling current waves from said conductor, repeaters for transmitting with substantially equal attenuation all of the frequencies throughout a wide range of frequencies, means for adding to the incoming signal wave derivatives thereof in such proportions as to produce a change in the wave form of the incoming signal waves prior to impressing them on said repeaters, and a transformer coupling between said repeaters and said means.

6. The combination with a telegraph conductor of a responsive device, means intermediate said conductor and said device for adding to the incoming wave derivatives thereof in such proportions as to make available at the terminals of said responsive device a wave form substantially like that of the original transmitted signal wave, and a series of directly connected thermionic amplifiers for amplifying said wave prior to its application to said responsive device.

7. The combination with a signaling transmission line which attenuates certain frequencies in the signal frequency range differently than other frequencies, of a multi-stage amplifier for amplifying said signals, and a plurality of correcting networks interposed between the various stages of said amplifier, each of which networks corrects in part for the unequal attenuation of said line.

8. The combination with a submarine cable of means for transmitting direct current signaling impulses thereover, a plurality of wave shaping networks each of which corrects in part for the unequal attenuation of signaling frequencies by said cable, and at least two of which perform their maximum correcting function in different parts of the signal frequency range, and means between said networks to prevent an adjustment of one from changing the wave correcting action of another.

9. The combination with a signal transmission line which distorts the signals, of signal receiving apparatus therefor comprising a plurality of high impedance electric discharge relays arranged in cascade, a substantially distortionless inductive electric coupling for impressing signaling energy upon the first of said relays, and impedance means for shaping the signal wave between said relays.

10. The combination with a signal transmission line which distorts the signals, of signal receiving apparatus therefor comprising an amplifying system, a transform-

er having its primary winding connected to said line, and its secondary connected to said amplifying system, signal correcting means bridged across the terminals of said primary winding and additional signal correcting means associated with said amplifying system.

11. The combination with three signal wave shaping means each having coupled 10 reactances and a transmission characteristic having two maxima, of means for causing said wave shaping means to operate in succession comprising wave transmitting means between adjacent ones of said shaping means 15 for electrically coupling them and also for preventing a change in the transmission characteristic of any one of the wave shaping means by a change in another.

12. The combination with a distorting 20 transmission line of three reactive wave correcting units, at least two of which act upon different frequencies in the signal frequency range, wave transmitting means between adjacent units for electrically coupling them 25 and also for preventing a change in the wave correcting action of any one of said units by a change in another one.

13. The combination with a submarine 30 cable, of means for impressing direct current signals thereon, an electric discharge amplifier having an anode, a cathode and an impedance control element, an inductive coupling transmitting all signal frequencies with substantially equal attenuation for 35 transferring energy from said cable to said amplifying means, and reactive signal wave shaping means in circuit between said cable and said inductive coupling for correcting in part at least for the signal wave distortion 40 produced by the cable.

14. The combination with a transmission 45 line of a duplex bridge terminal arrangement therefor, a transmitting battery connected to the apex of said bridge, a transformer having its primary connected across 50 said bridge, an electric discharge repeater having a cathode, an anode and an impedance control element, the terminals of the secondary of said transformer being connected 55 respectively to said cathode and to said impedance control element, and a conductive connection between said cathode and ground, and a grounded shield between the windings of said transformer to prevent duplex jar.

15. The combination with a transmission 60 line which greatly attenuates transmitted signals, of a conjugate terminal arrangement therefor comprising receiving and transmitting apparatus, said receiving apparatus being balanced with respect to transmitted current and including a high power amplifier for amplifying said greatly attenuated signals, a transformer associating said receiving apparatus with said cable and transmitting

70 apparatus, and a grounded shield between the primary and secondary windings of said transformer to prevent electrostatic changes in said transformer produced by said transmitting apparatus from reaching 75 said amplifier.

16. A system for equalizing for variable line attenuation of currents of different frequencies transmitted thereover comprising a circuit having conductors connected in series 75 relation with said line and a circuit connected across said conductors including a capacity and an inductance in parallel and a resistance, said capacity, inductance and resistance being proportioned with respect to one another and to the constants of said line so as substantially to counter-balance the effect on said currents of the unequal attenuating property of said line.

17. In a signaling system, a transmission line over which waves of higher frequencies become attenuated in transmission to a greater extent than waves of lower frequencies, means including a correcting network arranged to be traversed by the waves transmitted over said line for compensating for the difference in attenuation in said waves of different frequencies, and a unidirectionally conducting device connected between said line and said means.

18. In a transmission system, a line, the attenuation of which differs for different frequencies of current transmitted thereover, a two-stage amplifier for amplifying currents of different frequencies received over said line, and an attenuation equalizing circuit connected between the two stages of said amplifier for correcting for the unequal attenuation of the currents received over said line.

19. In combination, a line for transmitting currents of different frequencies with distortion, an amplifier associated with said line, a network associated with said line through said amplifier for correcting for the line distortion, said network comprising resistance, inductance and capacity, and having distorting properties for the transmitted currents substantially complementary to the 110 distorting properties of said line.

20. In a transmission system, a transmission line, the attenuation of which varies with the frequency of the currents transmitted thereover, a repeating system associated with said transmission line and comprising an impedance, and an auxiliary circuit the attenuation of which varies with the frequency of the transmitted currents in a manner complementary to that of the transmission line so that the resultant transmission over the line and auxiliary circuit is substantially constant over a desired range of frequencies, said auxiliary circuit being associated with the transmission line only 120 through said impedance.

21. In a transmission system, a transmission line over which different frequencies are transmitted with different attenuation, and an attenuation equalizer associated with the line, said attenuation equalizer comprising a parallel-series combination of resistance, inductance and capacity elements so proportioned and so related to each other and to the line, that all frequencies within a desired range of the currents transmitted over said line will be transmitted over the system with substantially uniform attenuation. 75
22. In a transmission system, a transmission line over which higher frequencies are transmitted with greater attenuation than lower frequencies, and an attenuation equalizer associated with said line, said attenuation equalizer comprising a parallel-series combination of resistance, inductance and capacity elements so proportioned and related to each other and the line as to increase the attenuation of lower frequencies transmitted over said line and through said equalizer to such extent that all frequencies within a desired range will be transmitted over the system with substantially uniform attenuation. 80
23. In a transmission system for transmitting currents of a range of frequencies, the combination of a line having different values of attenuation dependent on the frequency of current transmitted thereover, and an attenuation equalizer comprising a parallel series combination of resistance, inductance and capacity elements proportioned with respect to each other and the line constants to produce a total resultant attenuation for the system substantially constant over the range of frequencies transmitted. 85
24. In combination, a line for transmitting currents of different frequencies with distortion, an amplifier associated with said line, a network associated with said line through said amplifier for correcting for the line distortion, said network comprising resistance, inductance and capacity, and having distorting properties for the transmitted currents substantially complementary to the distorting properties of said line. 90
25. The combination with a line having a non-linear relation between the frequency of the wave components transmitted thereover and the variations in the phases of the transmitted wave components, of a localized network connected in series relation to said line and comprising more than one section and having a non-linear relation between the frequency of the wave components transmitted through it and the variations in the phases of the transmitted wave components, the phase variations introduced by said network being opposite in sense to those of said line and such that said network counteracts the effects of the said non-linear frequency-phase variations of said line. 95
26. The combination with a signal transmission line which produces distortion in the transmitted signal currents, of a localized network connected in series relation to the line, and composed of a plurality of sections each of which has a propagation constant reciprocal in nature to that of the line whereby said network at least partially corrects for the distortion produced by said line. 100
27. The combination with a signal transmission line having an attenuation which varies throughout the frequency range of the signals transmitted thereover, and having sufficiently great capacity to cause the velocity of wave propagation of the different frequency components in the signals to be sensibly different, of a network connected in series relation to the line and having more than one section, each section being of the type comprising a series and a shunt arm one of which contains reactance, the constants of said network being so related to those of said transmission line, that said network produces in the signal waves transmitted over the line and the connected network an attenuation which varies with frequency in a manner opposite to that of said transmission line, and also partially corrects for the effect of unequal rates of propagation of the different frequency components of the signaling waves of said line. 105
28. The combination as claimed in claim 26 in which the ratio of the series to the shunt impedance of each section of said network increases with increasing frequency throughout the signal frequency band. 110
29. The combination with a signal transmission line in which the rate of propagation of the higher frequency components in the signal frequency band transmitted thereover is higher than that of the lower frequency components, of a localized network connected in series relation with the line and comprising recurrent sections, said network having the property of propagating the lower frequency components of the signaling band at a higher rate than the higher frequency components. 115
30. The combination with a signal transmission line which produces amplitude and phase distortion in the transmitted signals of a localized network comprising an impedance in series relation to the line and a plurality of impedances in shunt relation to the line and connected to different points along said series impedance, said network having its constants proportioned with respect to those of said line to compensate for said amplitude and phase distortion in the transmitted signals. 120
- In witness whereof, I hereunto subscribe my name this 15th day of June A. D., 1918.
